W. LAFFOLD

FOLDING STAND FOR PASTE BUCKETS

Filed Dec. 20, 1923

INVENTOR:
WILLIAM LAFFOLD
By Higdon & Higdon
ATTORNEYS

UNITED STATES PATENT OFFICE.

WILLIAM LAFFOLD, OF ST. LOUIS, MISSOURI.

FOLDING STAND FOR PASTE BUCKETS.

Application filed December 20, 1923. Serial No. 681,706.

To all whom it may concern:

Be it known that I, WILLIAM LAFFOLD, a citizen of the United States, residing at St. Louis, in the State of Missouri, have 5 invented certain new and useful Improvements in Folding Stands for Paste Buckets, of which the following is a specification containing a full, clear, and exact description, reference being had to the accompanying 10 drawing, forming a part hereof.

My invention consists in the novel construction and combination of parts herein-after particularly described and distinctly claimed.

15 The object of my invention is to provide an improved stand for paper-hangers' paste-buckets, and which stand shall be adapted for use as an attachment to the well-known foldable, portable trestles now in use by 20 paper-hangers, so that the paste-bucket may set upon said stand, and be supported off of the floor at a convenient height, thereby preventing much stooping of the user in 25 dipping his paste-brush in the paste contained in said bucket, and which will also prevent paste from dripping from the paste-brush onto the floor or carpet in lifting the loaded brush from said paste-bucket to the wall-paper, and which invention shall be 30 simple in construction, durable in use, and of low cost to manufacture.

In the drawing:

Fig. 1 is a side elevation of a trestle having my invention attached thereto, the trestle being shown in dotted lines.

Fig. 2 is a top-plan view of same, and

Fig. 3 is a top plan-view of the trestle and the paste-bucket stand, folded in a small bundle, ready to be carried by the paper-hanger from job to job, or to be shipped.

Referring to the drawing by numerals, the numeral 1 designates the legs of the trestle, to one pair of which the inner ends of a pair of horizontal supporting-bars 2 45 are pivotally connected by pivot bolts or rivets 3.

The horizontal cross-bar 4 and the pair of supporting-legs which are designated by the numeral 5—5 are formed of a single straight 50 piece of strap-iron by bending the latter

in the form of the letter U (see Fig. 3), and each of the said legs 5 is pivotally connected near its upper end, adjacent the said integral cross-bar 4, to the adjacent outer ends of the respective horizontal supporting-bars 2, by means of a suitable rivet or bolt 6, so that the said legs 5 may be folded inwardly to the position which they are shown as occupying in Fig. 3, for the purpose of forming a compact bundle; the 55 said cross-bar 4 at the same time folding over the ends of the trestle, as shown in Fig. 3.

The paste-bucket 7 is supported during use, upon the horizontal supporting-bars 2 and said cross-bar 4, as shown in Fig. 1, so that the paper-hanger may conveniently dip his brush in the paste contained therein without stooping.

The numeral 8 designates a sleeve that is 70 slidably mounted upon the said horizontal supporting-bar 2 and is adapted to receive the inner ends of said legs 5 when the latter are in a folded position, and hold the latter in a folded position alongside of said bars. 75

The operation and advantages of my invention will be readily understood from the above description, except when the legs are in an extended or supporting position, as shown in Figs. 1 and 2, said legs are preferably inclined outwardly from the bottom up, both laterally and horizontally, so as to act as braces for all the connected parts to make the same less liable to be overturned accidentally.

80 The cross-bar 4 extends above the outer ends of the said supporting-bars 2, and when said legs 5 are extended, as shown in Fig. 2, the said cross-bar's inner edge contacts with the upper edges of the said supporting-bars, 85 and acts as a stop to limit the outward movement of the lower ends of said legs 5.

Said cross-bar 4 and said legs 5 are preferably made from a single piece of metal bent into the form shown in Fig. 3. 90

I claim:

A paper-hanger's paste-bucket stand, comprising a pair of horizontal supporting-bars, the inner ends of which are adapted to be pivotally connected to corresponding 100

trestle legs; and a cross-bar and a pair of supporting-legs formed integral from a single piece of strap-iron, and adapted to be pivotally connected to the outer free ends 5 of said supporting-bars; the free ends of said supporting-legs resting upon the floor when the said stand is in an unfolded posi-

tion; and said cross-bar contacting with the upper edges of said horizontal supporting-bars to limit the outward movement of said 10 supporting-legs.

In testimony whereof, I have signed my name to this specification.

WILLIAM LAFFOLD.
